SPREAD SHEET

Hunter E. Hooe, Athens, Ohio, assignor to The
McBee Company, Athens, Ohio, a corporation

Substituted for abandoned application Serial No.
739,451, April 4, 1947. This application April
4, 1951, Serial No. 219,195

1 Claim. (Cl. 129—16.5)

1

This application is a substitution for my application Serial No. 739,451 filed April 4, 1947, now abandoned.

The present invention relates to spread sheets whose component sheets are movably connected to each other to permit their relative spreading for the purpose of exposing part of the surfaces of the underlying component sheets.

Heretofore, the component sheets of a spread sheet have been slidably interlocked with each other through the use of additional devices, adding to the complexity of the spread sheet, limiting the number of component sheets which can be effectively incorporated in a spread sheet, enabling component sheets to become readily and inadvertently disconnected, and resulting in a comparatively loosely joined arrangement difficult to maintain in alignment with the component sheets are spread.

It is, accordingly, an object of the present invention to provide an improved and effective spread sheet which overcomes the aforesigned disadvantages.

Another object of the invention is to provide a spread sheet whose component sheets are slidably interlocked with each other by elements integral with, and constituting parts of, the sheets themselves, and without the necessity for employing any additional devices.

One form which the invention may assume is exemplified in the following description and illustrated by way of example in the accompanying drawings, in which:

Fig. 1 is a plan view of a component sheet prior to its connection to another component sheet.

Fig. 2 is a partial isometric view of the connection of one sheet to another.

Fig. 3 is an isometric view of two sheets coupled together prior to folding of the flaps of one sheet over one another.

Fig. 4 is a front isometric view of a group of component sheets in spread position.

As disclosed in the drawings, the spread sheet includes a plurality of superposed component sheets 10, each of which is preferably of rectangular shape and which may be made of suitable material, such as paper and the like, depending upon the specific manner in which the spread sheet is to be employed. Usually, the material is paper. Each sheet consists of a main body portion 11 on which suitable printed matter, lines, columns, etc., are to be placed, an end flap 12 foldable along a line 13 parallel to an edge 14 of the sheet, and an intermediate flap 15 foldable along a second line 16 parallel to the sheet edge.

2

In effect, each component sheet 10, when folded in interlocking relation with another sheet, may be considered as having three flaps, namely, a main body flap 11, an intermediate flap 15 and an end flap 12.

The intermediate flap 15 is provided with a guide slot 17 extending across the paper and bounded by two parallel lines 18, 18 terminating inwardly of the side edges 19 of the paper. A guide or retaining strip 20 may be disposed in this slot, being integral at its ends with the intermediate flap 15, and actually formed by two parallel line cuts 18 in the paper defining the sides of the slot 17.

Each sheet 10 also has a pair, or a plurality of pairs, of opposed tabs or tongues 21 formed therein in any suitable manner, as by arcuate or semi-circular paper cuts 22. It is to be understood, however, that the paper cuts 22 may be variously shaped and proportioned to form different shapes and sizes of tabs 21. The tabs 21 of each pair extend in opposite directions and are each adapted for pivoted or swinging movement about a hinge line 23 running along the ends of its cut 22. Such hinge lines 23 are substantially parallel to each other and to the sides 18 of the guide slot 17, being spaced apart a distance substantially equaling the width of the guide slot 17. A line 24 midway between the hinge lines 23 of an opposed pair of tabs 21 is spaced from the hinge line 16 of the intermediate flap 15 a distance substantially equal to the distance of the center line 25 of the guide slot from the flap hinge line 16. It is to be noted that the length of the slot 17 is substantially greater than the overall distance x across the tabs 21 along their hinge lines 23 to permit spreading of the sheets 10.

The component sheets 10 are interlocked with each other by projecting the tabs 21 on an underlying sheet forwardly of the plane of the paper by swinging them toward each other about their hinge lines 23. These tabs are then inserted through the opposite line cuts 18 defining the guide slot 17 and guide member 20, in the manner disclosed in Fig. 2, whereupon they are folded back away from each other against the back face of an adjacent component sheet flap 15 (see Fig. 3). The end flap 12 of such adjacent, component sheet may then be folded over the tabs 21 to hold them in flattened position against such upper sheet, and the main body flap portion 11 of the adjacent sheet swung downwardly about the hinge line 16 over the end flap 12 to hold it in position against the tabs 21.

In this manner, adjacent component sheets 10 are interlocked with respect to one another. Additional sheets may be interlocked with one another in the same fashion until the desired number of component sheets has been provided to form the spread sheet.

The tabs on one component sheet are effectively guided by the sides 18 of the slot 17 of an adjacent component sheet without the aid of the guide or retaining strip 20. This strip, however, also assists in holding the several sheets in proper assembled relation since they function as a barrier to removal of the tabs 21 through the slot 17.

The plurality of pairs of tabs 21 extend equidistantly on both sides of the vertical center line of each sheet, but, as noted above, their overall distance x is less than the length of the guide slot 17. This enables the component sheets to be spread in both directions from an overlying central coincident position by the distance that one sheet may move before the outer sides of the tabs engage the ends of the line cuts 18 defining the guide slot 17 and member 20.

Such distance is selected so as to produce the exposure of the desired extent of margin on each component sheet (see Fig. 4), depending upon the printed matter that may have been placed on the sheets and their columnar arrangement. Such margins are preferably of the same width on each component sheet to enable ready comparison or entry of data or information on the sheets to be made.

Any component sheet 10 may be removed through a reversal of the procedure required in effecting its assembly on an adjacent sheet. It is particularly to be noted that the sheets are assembled as a result of the formation of the parts from the sheet material itself, which parts remain integral with the sheet. No additional devices are employed whatsoever, thereby simplifying the spread sheet, making it less cumbersome and more easily assembled and disassembled, and enabling the parts to slidably en-

gage and interlock with one another in comparatively snug fashion, which holds them in alignment when in spread condition, assuring greater accuracy in making entries on the sheet or in comparing figures or data which may have been recorded thereon. The spread sheets cannot become inadvertently disconnected since the tabs 21 are held downwardly by the flaps 12 and also by the main flap portion 11 of each adjacent component sheet itself. The end flaps 12 assist in holding the tabs downwardly, but their use is not indispensable since the adjacent spread sheet will, by itself, hold the tabs in flattened position against the intermediate flap 15. The use of the end flap 12 is preferred, however, since it provides a smooth uninterrupted surface along which the tabs 21 slide, preventing their possible entanglement with the tabs of an adjacent sheet or the notches which such tabs leave when inserted through a slot 17.

While I have illustrated and described my invention in detail, it is to be understood that various changes may be made therein by those skilled in the art without departing from the spirit of the invention as defined in the appended claim.

Having thus described my invention, what I claim and desire to secure by Letters Patent is:

A spread sheet comprising a plurality of component sheets, each component sheet comprising a body portion upon which characters may be inscribed, adjacent outer and inner flaps integral therewith, said inner flap being provided with a pair of parallel slots, and a plurality of pairs of oppositely disposed and hinged tabs formed in the body portion adjacent the inner flap, adjacent pairs of component sheets being slidably interconnected by reception of the tabs of one sheet within the slots of the other sheet, and the outer flap of each component sheet being folded back against the tabs of an adjacent sheet.
